POROUS PLUG FOR STAYBOLTS AND THE
MANUFACTURE THEREOF

William T. Kilborn, Pittsburgh, and Frederick K. Landgraf, Crafton, Pa., assignors to Flannery Bolt Company, Bridgeville, Pa., a corporation of Delaware

Application April 30, 1936, Serial No. 77,186

5 Claims. (Cl. 85—1.5)

This invention relates to the porous bodies or plugs which are used in the firebox end of staybolts to close the opening in said bolts, and to a method of making the same.

5 In many boiler installations, it is desirable to use hollow staybolts. All steam boilers in service must periodically be inspected to ascertain if any of the staybolts are broken and whether the boiler is safe for its prescribed pressure. Where hollow staybolts are used, this inspection is made by cleaning and testing the holes in all of the staybolts to determine that they are clean and open throughout the length of the hole, and then placing the boiler under hydrostatic pressure. If any 10 hollow staybolts are broken or even fractured so that the fracture extends into the hole, the application of hydrostatic pressure to the boiler will cause water or moisture to appear in the holes, the amount of water, of course, depending on the 15 extent of the break or fracture. If the holes in the staybolts are not clean the evidence of leakage may not be detected, the accumulation of deposit on the inside of the hole absorbing or closing off the flow of water, particularly where 20 the fracture is quite small. In some cases, the so-called "tell-tale" hole extends throughout the full length of the bolt. In other cases, it extends throughout the major portion of the length and not entirely through the bolt. It is good practice 25 to drive porous plugs into the holes from the firebox end of the bolts when the boiler is ready to be put into service. These porous plugs, one form of which is shown in prior United States Patent 30 No. 1,428,541, dated September 12, 1922, serve to 35 prevent foreign matter from entering the hole from the firebox end of the boiler and filling it up. At the same time, the plug, being porous, will permit the escape of steam and/or water therethrough if the staybolt subsequently fractures.

40 The material used for making the porous plugs must be heat-resisting as well as porous. The bonded granular abrasive material which is generally used for the purpose must have a bond of 45 such character that the plugs will not disintegrate when they are subjected to the temperature of the inside of the firebox. Since the bond is completely fused in the forming of the plug, the only inherent means for holding the plug in the end of 50 the bolt is friction. It has been found in use that some plugs hold satisfactorily, whereas others will drop out, even though apparently tight in the first instance, after the boiler has been used for a period of time. This is especially so in locomotive boilers where in addition

to the severe operating conditions of the boiler, there is also added the jarring and vibration unavoidably incident to operating over rail joints, switches, etc.

5 It would be impractical to separately cement each plug in a hole, because it would have to be done with care and require skilled labor, and thereby increase the cost of installation. Also there would be danger that any satisfactory adhesive might obstruct the porosity of the material so as to render it substantially impervious to the passage of water therethrough.

10 The present invention contemplates a plug and a method of treating the plugs wherein the surface of the plug is provided with a material which increases the cohesion between the plugs and the inner wall of the tell-tale hole. According to the present invention, it is contemplated that another material be applied to the porous body which will not lessen the resistance of that body 15 to heat or impair the porosity thereof but which will increase the cohesion between the porous material and the walls of the hole.

15 The invention may be readily understood by reference to the accompanying drawing, in 20 which:

25 Figure 1 discloses a typical flexible staybolt assembly having a plug at the firebox end of the hole, the plug being treated in accordance with the present invention; and

30 Figure 2 is a perspective view of one of the plugs made in accordance with the present invention.

35 According to the present invention, the porous plugs are manufactured according to any well known method. When the manufacture of the plugs is otherwise completed, including the firing of the bonded granular material of which they are composed, and the shaping, a suitable sizing compound, paste or other form of substance is 40 applied to the plugs and completely dried thereon. The sizing or other substance employed must be of a character which will not destroy the porosity of the mass. It must be of a character which will dry out thoroughly, and must 45 be of a character which will leave, when dried, a deposit on the outside of the plug capable of increasing the cohesion between the plug and the inside of the hole.

50 As a typical example, the plugs after they are otherwise ready for use, are immersed in a solution of a waterglass, such as sodium or potassium silicate. The porous material absorbs the waterglass solution. The plugs are then dried. When the plugs are dry a very thin deposit of the 55

silicate is formed on the outside of the plug. It has been found that the drying of the solution throughout the mass of the plug does not impair its porosity.

5 When the plugs so treated according to this method are driven into the open ends of the staybolts, they fit much more closely to the walls of the hole and there is greater cohesion between the plug and the inside walls of the hole than 10 where the friction of the bonded abrasive material alone is relied upon. This has not only been borne out in actual use, but has been borne out on specially constructed test panels, such panels having a large number of staybolts mounted 15 thereon. Arrangements are provided for heating and cooling the panel and an air hammer is provided for vibrating the panel. Through this arrangement, conditions simulating firebox conditions can be obtained but of a more intensified order. It has been found that porous plugs 20 processed as described above will remain in the holes on the test panel under conditions which result in a very great percentage of the untreated plugs jarring out. To the eye, however, 25 the treated plugs do not differ in appearance from the untreated ones, the amount of silicate deposit being slight. Moreover, the plugs so treated can be broken out of the holes for inspection purposes where necessary as readily as the 30 untreated ones, there being no actual adhesion or cementing of the plugs to the interior of the hole.

While the water-soluble silicates make the best material so far as our experiments up to the 35 present time have indicated, other materials may also be used. For example, the plugs may be immersed in a sugar solution and dried before use. In the subsequent operation of a boiler, the sugar carbonizes, but the resulting film of carbon nevertheless serves to increase the cohesion between the plug and the walls of the hole into which the plug is driven. Likewise, other organic 40 materials may be used which will also carbonize as, for instance, a thin solution of gum tragacanth. A solution of ordinary table salt or sodium chloride may also be used, the glaze-forming quality of the salt being utilized. Various ceramic slips or compositions may also be 45 used. The foregoing are merely typical of a great many other materials which may be used. The material used must be either dusted onto the exterior of the porous body or if used as a solution must be of a character which will not 50 upon soaking into the porous material, render

the same non-porous. The plugs are of relatively small diameter, and hence care must be taken that the material used, if it soaks into the body of the material will not destroy or seriously impair its porosity.

5 In the drawing, 2 designates a typical hollow staybolt having a tell-tale hole 3 opening at the firebox end and having a plug 4 driven into the end thereof, the plug being of a character herein described. In Figure 2, the plug 4 is shown detached from the staybolt. It is preferably slightly tapered to facilitate its being entered into the hole of the staybolt and driven in.

The material used for treating the plugs must be a material which can be dried so that the 15 plugs after being manufactured and treated, can be shipped in a dry state to the user.

It will be understood that various changes and modifications may be made in the invention within the scope of the following claims.

20 We claim:

1. A porous plug for staybolts comprising a refractory body of a porous character having a surface coating of a material thereon of a glaze-like nature for increasing the frictional contact 25 between the plug and the wall of the hole in the bolt.

2. A porous plug for staybolts comprising a refractory body of a porous character having a water-soluble silicate applied to the outer surfaces thereof.

3. A porous plug for staybolts comprising a refractory body of a porous character having a dried coating forming a surface film thereover of a character which does not detrimentally affect 35 the porosity of the plug as a whole and which increases the cohesion between the plug and the bolt of the staybolt into which the plug is entered.

4. The method of treating porous plugs for use 40 in closing the telltale holes of boiler staybolts which comprises immersing the plugs in a solution capable of leaving a deposit on the porous material of a character which increases the cohesion between the plug and the hole into which the 45 plug is driven but which does not appreciably affect the porosity of the plug.

5. The method of treating porous plugs for use 50 in closing the telltale holes of boiler staybolts which comprises immersing the plugs in a solution of a water-soluble silicate and thereafter drying the plugs.
